UNITED STATES PATENT OFFICE.

JOSEPH R. GLENNON AND LOUIS DUPUIS, OF NEW BEDFORD, MASSACHUSETTS; SAID DUPUIS ASSIGNOR TO SAID GLENNON.

DOFFER GUARD AND OIL-WELL COVER FOR SPINDLE SUPPORTS FOR SPINNING AND LIKE MACHINES.

1,425,521.

Specification of Letters Patent. Patented Aug. 15, 1922.

Application filed June 8, 1921. Serial No. 475,915.

To all whom it may concern:

Be it known that we, JOSEPH R. GLENNON and LOUIS DUPUIS, citizens of the United States, residing at New Bedford, in the county of Bristol and State of Massachusetts, have invented new and useful Improvements in Doffer Guards and Oil-Well Covers for Spindle Supports for Spinning and like Machines, of which the following is

10 a specification.

The present invention relates to spindles for spinning machines, and particularly to doffer guards for retaining the spindle in the bolster. It contemplates a combined doffer guard and oil well cover, so assembled and disposed as that the doffer guard will be locked against accidental shifting or displacement, and yet may be readily shifted by an operator to permit removal of 20 the spindle from its bolster.

The construction is such as to minimize danger of breakage of any of the parts and to eliminate danger of breakage of the bolster casing or the oil well post, all likelihood 25 of breakage being confined to the doffer guard and oil well cover which, under the present construction, may be very quickly and readily replaced at small expense.

Broadly, it is old to provide doffer guards 30 and oil well covers so combined as to prevent accidental unshipping of the spindles in operation, and at the same time protect the oil wells, and we do not claim broadly this as our invention, as the same general 35 idea has been worked out in various constructions, but the present development has certain features of novelty and certain advantages over doffer guards now known to us, due to the construction and assemblage 40 which we have invented.

In order that the invention may be clear to those skilled in the art, we have shown in the accompanying drawings one physical embodiment of our invention, but it will be 45 understood that this is illustrative and not restrictive, as such changes as are merely equivalent mechanical expedients, and such departures as are obvious variations of the construction herein disclosed may be made 50 without going outside the range of our invention.

In said drawings:

Figure 1 is an elevation of a bolster casing with so much of a spindle thereon as is necessary to an understanding of our invention, the doffer guard being shown in operative position. 55

Figure 2 is an elevation similar to Fig. 1, the doffer guard being shown in its inoperative position. 60

Figure 3 is a plan view of the mechanism with the parts in the position shown in Fig. 1.

Figure 4 is a plan view of the mechanism with the parts in the position shown in 65 Fig. 2.

Figure 5 is an elevation at right angles to and looking from the right of Fig. 1.

Figure 6 is a view at right angles to and looking from the right of Fig. 2. 70

Figure 7 is a detail perspective view of the oil well cap.

Figure 8 is a detail perspective view of the oil well cap supporting post.

Referring to the drawings by numerals, 75 like numbers indicating like parts in the several views, 10 designates a bolster casing of any ordinary or usual construction, and 11 indicates any ordinary spindle with the whorl 12, arranged in the usual manner. 80

The bolster casing 10 has the usual body portion or flange 13 which seats upon the bolster rail and from the body 13 projects the oil reservoir which delivers to the bolster casing, said oil reservoir having a horizontal section 14 delivering to the casing and the vertical reservoir or receiving section 15 which has an open top to permit filling or oiling. 85

The parts thus far described are old and 90 well known in the art.

The oil well post 15 is provided with an enlarged section 16 on its inner side adjacent the whorl 12, this enlargement 16 being of a size to provide an area in which 95 is formed a receiving socket 17, which socket is of sufficient depth and so formed, as, for example, by screw-threading, as to receive and retain the vertical limb 18 of a substantially L-shaped doffer guard, the 100 horizontal limb 19 of which guard is of sufficient length to project inwardly over the

whorl 12 when the guard is in the position shown in Figures 1, 3 and 5.

This guard may be readily formed by bending a piece of heavy wire or small rod, and screw threading or otherwise fashioning the vertical limb 18 of the guard to fit the socket 17 and be retained therein, but freely rotatable to permit the guard to be shifted from the operative position shown in Figure 10 to the inoperative position shown in Figure 2, so that an effective doffer guard, operative to engage the whorl 12 when in one position, and capable of being thrown to an inoperative position, as shown in Figures 2, 15 4, and 6, to permit removal of the spindle, is provided.

The horizontal section 19 of the L-shaped guard is provided with an oil well cover 20, the forks or arms of which straddle the 20 horizontal limb 19 of the guard as shown clearly in Figures 3 and 4, and are preferably pinned thereto by the pivot pin 21, so that the cover 20 is free to swing from the full line position shown in Figure 1, to an 25 angle relative to the guard, as indicated by dotted lines in Figure 1.

The oil well cover 20 has at its forward covering end the enlarged portion, of sufficient area to cover the oil hole in the vertical member or oil post 15, and is provided with means for locking the cover and the L-shaped guard against angular movement or rotation when such oil well cover is in its closed position, as shown in full lines in 30 Figures 1, 3 and 5. The particular means here shown for locking the parts against angular movement comprises the flanges 22, which depend from the free end of the cover 20 and, when it is in closed position, straddle the oil 35 well post 15 and engage on either side thereof, so that lateral movement of the cover and its supporting post in either direction is impossible. This prevents any accidental shifting of the parts, and the L-shaped doffer guard can be swung to the inoperative 40 position shown in Figure 2, only after the oil well cover 20 has been tilted to clear the flanges 22 from engagement with the top of the oil well posts. This effectually prevents any shifting of the parts except when 45 the operators manipulate them for the purpose of removing or replacing spindles in the bolster casings.

It will be observed that with this construction, the L-shaped member forms a very substantial and effective doffer guard, that L-shaped member taking the strain of impact from the whorl 12 either during the spinning operation or during doffing, and 50 prevents unshipping of spindles due to vertical lift during running or during the removal of cops from the spindles. At the same time, a guard is provided which may be very easily and quickly shifted by simply raising the oil well cover to clear the

cover flanges from the oil well post, and rotating the L-shaped guard in its socket to bring it to the inoperative position shown in Figure 2.

Preferably the L-shaped doffer guard will 70 be made as shown with its foot threaded, for this provides for rotatable shifting of the guard and the oil well cover, and affords the necessary vertical adjustment, for it will be seen that the forked cover is so mounted 75 (see Figures 3 and 4) on the L-shaped member that it will accommodate itself to a relatively wide range of vertical adjustments of the member or guard, the slot between the forks of the cover being of sufficient 80 length to give clearance and permit the cover plate to take its position on the oil well post 15 with its flanges 22 in engagement therewith regardless of the vertical adjustment of the doffer guard. 85

It will be observed that the L-shaped member or guard, which may be made of material of sufficient strength to resist breakage under ordinary impact, sustains the entire force of the blow of the whorl and 90 since this is separately formed from the oil well post and oil well cover, if breakage should occur, it will be breakage of the L-shaped guard, leaving the oil well cover and the oil post, which is 95 formed integral with the bolster casing, in condition for use, and replacement of the entire bolster casing or the oil well cover is done away with, the only repair necessary being the replacement of the relatively 100 small, inexpensive, L-shaped doffer guard.

It will be understood that the invention can be applied to any spindle regardless of type or work done, to which it may be adapted, to secure the results hereinbefore 105 described, and we do not limit ourselves to any specific type of spindle.

We claim:

1. In a device of the class described, the combination of a bolster casing, an oil well 110 post extending therefrom, a substantially L-shaped doffer guard mounted at its lower end on said post and shiftable thereon from operative to inoperative position relative to a spindle whorl, and an oil well cover 115 mounted on and supported by said guard and shiftable from an operative to an inoperative position relative to the oil well.

2. In a device of the class described, the combination of a bolster casing, an oil well 120 post extending therefrom, a substantially L-shaped doffer guard mounted at its lower end on said post and rotatable from an operative to an inoperative position relative to a spindle whorl, and an oil well cover 125 mounted on said guard and vertically shiftable from an operative to an inoperative position relative to the oil well.

3. In a device of the class described, the combination of a bolster casing, an oil well 130

- post extending therefrom, a substantially L-shaped doffer guard mounted at its lower end on said post and rotatable from an operative to an inoperative position relative to a spindle whorl, and an oil well cover pivotally mounted on the horizontal limb of said guard and shiftable from an operative to an inoperative position relative to the oil well.
- 10 4. In a device of the class described, the combination of a bolster casing, an oil well post extending therefrom, a substantially L-shaped doffer guard mounted at its lower end on said post and shiftable from an operative to an inoperative position relative to a spindle whorl, an oil well cover mounted on said guard and shiftable from an operative to an inoperative position relative to the oil well, and means to lock the said doffer guard against movement when said oil well cover is closed.
- 15 5. In a device of the class described, the combination of a bolster casing, an oil well post extending therefrom, a substantially L-shaped doffer guard mounted at its lower end on said post and shiftable from an operative to an inoperative position relative to a spindle whorl, an oil well cover mounted on said guard and shiftable from an operative to an inoperative position relative to the oil well, and means on said cover to lock the said doffer guard against movement when said oil well cover is closed.
- 20 6. In a device of the class described, the combination of a bolster casing, an oil well post extending therefrom, a doffer guard rotatably mounted on said post, an oil well cover pivotally mounted on said guard, and means on said cover engaging said post to prevent rotation of said guard when said cover is closed.
- 25 7. In a device of the class described, the combination of a bolster casing, an oil well post extending therefrom, a doffer guard rotatably mounted on said post, an oil well cover pivotally mounted on said guard, and a flange on said cover engaging said post to prevent rotation of said guard when said cover is closed.
- 30 8. In a device of the class described, the combination of a bolster casing, an oil well post extending therefrom, a doffer guard rotatably mounted on said post, an oil well cover pivotally mounted on said guard, and flanges straddling said post to prevent rotation of said guard when said cover is closed.
- 35 9. In a device of the class described, the combination of a bolster casing, an oil well post extending therefrom, a substantially L-shaped doffer guard rotatably mounted in said post and vertically adjustable therein, and an oil well cover pivotally mounted on the horizontal limb of said doffer guard.
- 40 10. In a device of the class described the combination of a bolster casing, an oil well
- post extending therefrom, a substantially L-shaped doffer guard having its vertical limb screw-threaded in said post for vertical and angular movement, an oil well cover having a forked end pivoted to said doffer guard, and locking flanges on the free end of said cover embracing said post when said cover is closed.
- 45 11. In a device of the class described, the combination of a bolster casing, an oil well post extending therefrom, an oil well cover pivotally and rotatably mounted on said post, and a flange on said cover engaging said post to lock said cover against rotation when in closed position.
- 50 12. In a device of the class described, the combination of a bolster casing, an oil well post extending therefrom, an oil well cover pivotally and rotatably mounted on said post, and flanges on said cover straddling said post to lock said cover against rotation when in closed position.
- 55 13. In a device of the class described, the combination of a bolster casing, an oil well post extending therefrom, a doffer guard mounted on said post and shiftable thereon from operative to inoperative position relative to a spindle whorl, and an oil well cover movably supported by said guard and shiftable from an operative to an inoperative position relatively to the guard and the oil well.
- 60 14. In a device of the class described, the combination of a bolster casing, an oil well post extending therefrom, a doffer guard mounted on said post and rotatable from an operative to an inoperative position relative to a spindle whorl, and an oil well cover movably mounted on said guard and vertically shiftable from an operative to an inoperative position relative to the oil well and the guard.
- 65 15. In a device of the class described, the combination of a bolster casing, an oil well post extending therefrom, a doffer guard mounted on said post and rotatable from an operative to an inoperative position relative to a spindle whorl, and an oil well cover pivotally supported by said guard and shiftable from an operative to an inoperative position relative to the oil well and the guard.
- 70 16. In a device of the class described, the combination of a bolster casing, an oil well post extending therefrom, a doffer guard mounted on said post and shiftable from an operative to an inoperative position relative to a spindle whorl, an oil well cover movably mounted on said guard and shiftable from an operative to an inoperative position relatively to the oil well and the guard, and means to lock said doffer guard against movement when said oil well cover is closed.
- 75 17. In a device of the class described, the combination of a bolster casing, an oil well post extending therefrom, a doffer guard

mounted on said post and shiftable from an operative to an inoperative position relative to a spindle whorl, an oil well cover movably mounted on said guard and shiftable from 5 an operative to an inoperative position relatively to the oil well and the guard, and means on said cover to lock said doffer

guard against movement when said oil well cover is closed.

In testimony whereof we have hereunto set our hands.

JOSEPH R. GLENNON.
LOUIS DUPUIS.
